UNITED STATES PATENT OFFICE.

HENRY JOSEPH LE PUL, OF NEW YORK, N. Y.

AEROPLANE.

1,394,314.

Specification of Letters Patent.

Patented Oct. 18, 1921.

Application filed May 20, 1920. Serial No. 382,968.

To all whom it may concern:

Be it known that I, HENRY JOSEPH LE PUL, a citizen of the United States, and a resident of the city of New York, borough 5 of Manhattan, in the county and State of New York, have invented a new and Improved Aeroplane, of which the following is a full, clear, and exact description.

The object of the invention is to provide a 10 new and improved aeroplane arranged to enable the aviator to readily vary the angle of incidence of a wing with a view to insure an easy taking off or making a landing within a comparatively short space.

Another object is to permit the aviator to 15 vary the angle of incidence during flight to compensate for the variation of the load due to the consumption of the fuel thereby being able to maintain a uniform rate of speed.

With these and other objects in view, the 20 invention consists of certain novel features of construction as hereinafter shown and described and then specifically pointed out in the claims.

A practical embodiment of the invention 25 is represented in the accompanying drawings forming a part of this specification, in which similar characters of reference indicate corresponding parts in all the views.

Figure 1 is a rear elevation of the aeroplane with parts shown in section on the line 1-1 of Fig. 2;

Fig. 2 is a plan view of the same with a portion of the upper wing broken out;

Fig. 3 is an enlarged sectional side elevation of the upper wing on the line 3-3 of Fig. 2;

Fig. 4 is a similar view of the same with the rear portion of the wing swung downward to vary the angle of incidence;

Fig. 5 is an enlarged sectional side elevation of a portion of the upper wing;

Fig. 6 is a transverse section of the same on the line 6-6 of Fig. 5; and

Fig. 7 is an enlarged sectional plan view of the actuating mechanism for the movable rear portion of the upper wing, the section being on the line 7-7 of Fig. 1.

The aeroplane illustrated in Figs. 1 and 2 50 is in the form of a biplane, but I do not limit myself to this particular form of aeroplane as the principal improvement is in the form of a wing, as hereinafter more fully described. As shown, the fuselage 10 of the 55 aeroplane is provided with the usual cockpit

11 and supports a top wing 12, a bottom wing 13 and a suitable landing gear 14 together with rudders of usual construction, not shown. The upper wing 12 is provided with top and bottom coverings 20 and 21 60 which may be of textile fabrics or metal or other suitable material, and the said coverings are mounted on the main frame comprising a forward wing beam 25, a rear wing beam 26 and ribs 27 connecting the beams 25 and 26 with each other and projecting beyond the front beam 25, as plainly indicated in Fig. 3.

The rear wing beam 26 is provided with bearings 30 in which is journaled a shaft 31, 70 preferably made hollow and forming part of a swing frame 32 provided with ribs 33 preferably in alignment with the ribs 27 and extending rearwardly with the rear portions of the top and bottom coverings 20 and 21 75 overlying the swing frame and being slidably connected therewith, as hereinafter more fully explained. The rear ends of the coverings 20 and 21 project beyond the rear of the swing frame 32 and the projecting portions are provided at their opposite faces with reinforcing and rubbing members 35 and 36 slidably engaging one another, as will be readily understood by reference to Figs. 3 and 4. The swing frame 32 80 is normally in the position shown in Fig. 3 to provide a wing of usual shape, but when it is desired to vary the angle of incidence then the swing frame 32 is swung downward (see Fig. 4) whereby the rear portions 85 of the coverings 20 and 21 are flexed in a like direction thus varying the angle of incidence of the wing for taking off or alighting purposes. It is understood that the swing frame 32 extends throughout the span of the wing 90 12 and the chord or width of the flexible portion of the wing is somewhat in excess of that of the usual ailerons 40 mounted on the swing frame at cut-out portions of the coverings 20 and 21, as will be readily understood by reference to Fig. 2. The ailerons 95 40 are of usual construction and are controlled in the usual manner by the operator but wholly independent of the swinging movement given to the swing frame 32 employed for varying the angle of incidence of the wing 12.

The shaft 31 is provided above the fuselage 10 with a bevel gear wheel 50 (see Figs. 1 and 2) in mesh with a bevel gear wheel 51 110

secured on the upper end of a shaft 52 journaled in suitable bearings 53, 54 arranged on the fuselage 10. On the lower end of the shaft 52 is secured a worm wheel 55 in mesh with a worm 56 secured on a shaft 57 journaled in a suitable bearing 58 (see Fig. 7) and provided with a crank arm 59 under the control of the aviator to permit the latter to turn the shaft 57 with a view to impart a rotary motion to the shafts 52 and 31 to swing the swing frame 32 downward (see Fig. 4) into an angular position or back to normal position, as shown in Fig. 3.

In order to facilitate the flexing of the rear portions of the coverings 20 and 21 use is made of flat springs 60 and 61, of which the flat springs 60 are on the under side of the top covering 20 and overlie the ribs 27 and 33 while the springs 61 are on the top of the bottom covering 21 and underlie the ribs 27 and 33. The front portions of the springs 60 and 61 are fastened by rivets or other fastening devices 62, 63 to the coverings 20 and 21 and the ribs 27, and the rear portions 25 of the springs 60 and 61 are slidably connected with the ribs 33 and are for this purpose fastened by bolts or rivets 65, 66 to buttons 67, 68 slidably mounted on the top and bottom flanges 69, 70 of the ribs 33. The buttons 67 and 68 are provided with lugs 71 and 72 slidably fitting into grooves 73, 74 formed in the top and bottom flanges 69 and 70 of the ribs 33, as will be readily understood by reference to Figs. 5 and 6. The rivets 65 and 66 also engage the coverings 20 and 21 to fasten the springs 60 and 61 in position on the coverings.

From the foregoing it will be seen that the rear portion of the wing 12 can be readily swung down or up throughout the entire span of the wing and held locked in the adjusted position owing to the worm gearing described. It will also be noticed that the ailerons 40 form part of the movable portion 45 of the wing but have independent motion thereof. It will further be noticed that the coverings 20 and 21 are of unbroken continuity the same as in ordinary wings as now generally constructed, but the rear portions of the said coverings are readily flexed on giving a swinging movement to the swing frame 32.

It is understood that the lower wing 13 may be constructed like the upper wing and the rear portions of the wings coupled

together and actuated from the shaft 57 to operate in unison, as indicated in Fig. 1.

Having thus described my invention, I claim as new and desire to secure by Letters Patent:—

1. In an aeroplane, a wing comprising a relatively fixed front portion, a relatively movable rear portion and an aileron carried by the rear portion and independently movable, the aileron extending from a point intermediate of the length of the wing to the outer end of the same. 65

2. In an aeroplane, a wing comprising a relatively fixed front portion, a relatively movable rear portion and an aileron carried by the rear portion and independently movable, the aileron extending from a point intermediate of the length of the wing to the outer end of the same, means for adjusting the rear portion of the wing and independent means for adjusting the aileron. 70

3. In an aeroplane, a wing comprising a relatively fixed front portion, a relatively movable rear portion extending substantially the full length of the front portion 80 and having its outer rear portion cut away, and an aileron filling the said cut away portion and movable up and down at its rear edge independently of the said movable rear portion of the wing. 85

4. In an aeroplane, a wing comprising a fixed member, an adjustable member pivoted to the fixed member and provided with grooves, and springs extending across the joint of the members on opposite sides of the joint, each spring having one end secured to the fixed member, and buttons to which the other ends of the springs are secured, said buttons being provided with lugs 90 slidably mounted in the grooves of the pivoted member.

5. In an aeroplane, a wing comprising an inner frame having forward and rear beams and ribs connecting the beams, the rear beam being provided with bearings, an outer 100 frame having a hollow shaft mounted in the said bearings, springs extending across the joint of the frames and each having one end fixed to one frame and its other end slidably secured to the other frame, upper 105 and lower coverings for the frames, the covering being slidably connected with the outer pivoted frame.

HENRY JOSEPH LE PUL.
